US00D912483S

(12) **United States Design Patent** (10) Patent No.: **US D912,483 S**
(45) Date of Patent: **** Mar. 9, 2021**

(54) **WRENCH**

(71) Applicant: **Milwaukee Electric Tool Corporation**,
Brookfield, WI (US)

(72) Inventors: **Joseph M. DeBaker**, Greenfield, WI
(US); **Andrew M. Tuchscherer**,
Wauwatosa, WI (US); **Steven W.
Hyma**, Milwaukee, WI (US)

(73) Assignee: **Milwaukee Electric Tool Corporation**,
Brookfield, WI (US)

(**) Term: **15 Years**

(21) Appl. No.: **29/670,466**

(22) Filed: **Nov. 15, 2018**

(51) LOC (13) Cl. **08-05**

(52) U.S. Cl.

USPC **D8/25**; D8/21

(57) **CLAIM**

We claim the ornamental design for a wrench, as shown and
described.

DESCRIPTION

FIG. 1 is a front perspective view of the claimed design;
FIG. 2 is a rear perspective view of the claimed design of
FIG. 1;

FIG. 3 is a front view of the claimed design of FIG. 1;
FIG. 4 is a rear view of the claimed design of FIG. 1;
FIG. 5 is a left side view of the claimed design of FIG. 1;
FIG. 6 is a right side view of the claimed design of FIG. 1;
FIG. 7 is a top view of the claimed design of FIG. 1; and,
FIG. 8 is a bottom view of the claimed design of FIG. 1.
The ornamental design which is claimed is shown in solid
lines in the drawings. The broken dot-dash lines define
boundaries of the claimed design and form no part thereof.
The broken lines in the drawings are for illustrative purposes
only and form no part of the claimed design.

1 Claim, 5 Drawing Sheets
